D12-18. OR D 7,166 EX

DESIGN FOR STREET-CARS.

Design No. 7,166, dated February 10, 1874

C.M. MURCH.

Design for a Street-Car.

FIG. 1.

FIG. 2.

UNITED STATES PATENT OFFICE

CHAUNCEY M. MURCH, OF CINCINNATI, OHIO.

DESIGN FOR STREET-CARS.

Specification forming part of Design No. 7,166, dated February 10, 1874; application filed January 5, 1874.
[Term of Patent 14 years.]

To all whom it may concern:

Be it known that I, CHAUNCEY M. MURCH, of Cincinnati, Hamilton county, Ohio, have invented a new and ornamental Design for a Street-Car, of which the following is a description:

Figure 1 is a side elevation, and Fig. 2 is a horizontal section, of my car, of which—

A B C represent the body proper. D D' represent the wheel-guard. E E represent the roof. The body is of an approximately-elliptical shape in its horizontal section, imparting to the car a graceful and remarkably attractive appearance. The rear end B is contracted to make a graceful appearance about the wheels, and again expands to the extreme back end, affording a pleasing approach, one on each side of the rear guard C. The wheel-guards D D' are tastefully ornamented, as clearly shown in Fig. 1.

I claim as my invention—

1. The design for a street-car body, embracing the enlarged portion A, contracted portion B, and enlarged portion C, substantially as set forth.

2. The design for the wheel-guards D D', embracing the external ornamentation, substantially as set forth.

3. The general design for a street-car, consisting of body A B C, wheel-guards D D', and roof E, the rear wheels being partially concealed in recesses in the sides of the contracted rear portion of the body, all as shown and specified.

In testimony of which invention I hereunto set my hand.

CHAUNCEY M. MURCH.
